PORTABLE GAS STERILIZER

Frank E. Power, 23 Sunset Road, Ashland, Mass.

Filed Oct. 2, 1964, Ser. No. 81,998

Term of patent 14 years

(Cl. D83—1)

Fig. 1.

Fig. 2.

Fig. 3.

FIG. 1 is a perspective view of the front of a portable gas sterilizer showing my new design,

FIG. 2 is a perspective view of the rear side thereof; and

FIG. 3 is a side view thereof.

The portable gas sterilizer presents a substantially identical appearance from either side.

I claim:

The ornamental design for a portable gas sterilizer, as shown and described.
